Alexander E. Blumenthal, 1382 Woodbine St.,
Pittsburgh, Pa.

Filed Apr. 29, 1959, Ser. No. 55,694

Term of patent 7 years

(Cl. D33—3)

Fig. 1.

Fig. 2.

Fig. 3.

Figure 1 is a view in perspective of a telephone secretary embodying my design in closed position;

Fig. 2 is a view in perspective thereof in open position; and

Fig. 3 is a view in perspective thereof showing the underside of the secretary in closed position.

The dominant features of the telephone secretary design are shown by solid lines on the drawing.

The side not shown is like the side shown while the back is conventionally flat.

I claim:

The ornamental design for a telephone secretary or similar article, as shown and described.
